(57) **CLAIM**

The ornamental design for an implant for medical applications, as shown and described.

DESCRIPTION

FIG. 1 is a left side elevation of an implant for medical applications showing our new design;

FIG. 2 is a right side elevation thereof;

FIG. 3 is a top plan view thereof;

FIG. 4 is a bottom plan view thereof;

FIG. 5 is a front perspective view thereof;

FIG. 6 is a rear perspective view thereof;

FIG. 7 is a cross-sectional view thereof taken along reference lines 7—7 in FIG. 1; and,

FIG. 8 is another cross-sectional view thereof taken along reference lines 8—8 in FIG. 3.

The broken line shown in the figure drawings is included for the purpose of illustrating the boundary of claimed subject matter and structural environment and form no part of the claimed design.

The single dot dashed lines shown in FIGS. 1—8 form the boundary of the claimed design and the remaining dashed lines illustrate environment and form no part of the claimed design.
